UNITED STATES PATENT OFFICE.

WILLIAM R. ORMES, OF WALTHAM, MASSACHUSETTS, ASSIGNOR TO UNIVERSAL SAFETY TREAD COMPANY, OF BOSTON, MASSACHUSETTS, A CORPORATION OF MASSACHUSETTS.

TREAD FOR STAIRS AND THE LIKE.

1,319,895.

Specification of Letters Patent.

Patented Oct. 28, 1919.

Application filed November 17, 1917. Serial No. 202,676.

To all whom it may concern:

Be it known that I, WILLIAM R. ORMES, of Waltham, in the county of Middlesex and State of Massachusetts, a citizen of the 5 United States, have invented a new and useful Improvement in Treads for Stairs and the like, of which the following is a specification.

Treads have been made of a base plate of 10 hard metal combined with strips of an abrasive material, such as an abrasive composition or comparatively soft metal such as lead, the plate being perforated by suitable mechanism, the edges of the perforations 15 being bent up to form flanges or points between which the abrasive material is held. The abrasive material is held in place by the flanges and at the perforations is more or less supported by the flooring or stair on 20 which the tread is laid.

These treads have come into very universal use, more particularly for the purpose of resurfacing the floor or stair tread. Where, however, the foundation (*i. e.*, the 25 flooring or stair) on which the tread is laid is worn away so as not to be flat and smooth so that it does not serve as a support for the abrasive material, this material is liable, especially if it is brittle, to be broken down 30 through the opening in the plate, thus making the tread as a whole imperfect.

My invention is intended to overcome this fault, and it comprises a plate provided with flanges to hold the abrasive material and 35 also what I term bridge-pieces located between opposing flanges and which act as a support for the abrasive material which lies between the flanges so that the abrasive material does not rely on the flooring or tread 40 for its support.

My invention will be understood by reference to the drawings, in which—

Figure 1 shows a base plate, embodying my invention, in plan;

45 Fig. 2 showing the completed device after the softer material has been put in place.

Fig. 3 is a section on line 3—3 of Fig. 1.

Fig. 4 is a section on line 4—4 of Fig. 2.

50 Fig. 5 is a section on line 5—5 of Fig. 1, and

Fig. 6 is a section on line 6—6 of Fig. 2.

Fig. 7 is a similar section of a tread comprising a sheet of abrasive composition.

The base plate will be understood from Figs. 1, 3 and 5. It comprises essentially a 55 plate A of metal of suitable thickness, preferably sheet metal, from which there have been punched or otherwise formed flanges a, the relative and preferred arrangement of which is shown in Figs. 3 and 5, that is, they 60 are punched up from the under side of the base plate A, forming openings a¹.

Heretofore when flanges of this nature have been punched in this way the two opposing flanges have left a single opening 65 between them, but in the present case each flange on being bent up leaves its own opening a² so that what I have termed a bridge-piece or bridge a² is left between them. These bridges serve as an under support for 70 the abrasive material, which may be a strip B (see Fig. 6) or a sheet B¹ (see Fig. 7). In Fig. 6 the strips B are shown held between the flanges a, while in Fig. 7 the flanges serve to hold the material in place against 75 the plate A. In assembling the parts the abrasive material B is inserted in place and the flanges are preferably bent toward each other (see Fig. 6) so that they bite into the abrasive material and so hold it in place, and 80 preferably the abrasive material is sufficient in size to provide a cap or wearing surface b which shall take the first wear of the tread and so prolong its life, and be more or less supported on the flanges. In Fig. 7 the 85 abrasive material is shown in the form of a level sheet which is applied to the plate A in plastic form and thereafter hardened. In either case the abrasive material is supported from below by the bridge-pieces and 90 will not tend to disintegrate, and in the tread shown in Fig. 7 it is supported along substantially its entire under surface.

Thus the bridge-piece a² will help to sustain the non-slipping members B, B¹ and 95 prevent these members or portions thereof from being driven through and disappearing below the top edges of the flanges. Moreover, the driving of the wearing material into place in the construction of the tread of Fig. 6 tends to clench it under the bridge-piece a² as well as at the corners of the openings a¹. When putting the wearing surface into place the flanges a are preferably bent toward each other so as to hold the wearing 100 surface from working upward out of place, 105

and when the abrasive member is sufficiently large the flanges bite into the abrasive member.

It is evident that what I have called the bridge-pieces may be otherwise constructed. They are as shown portions of the plate A, which have not been forced out of place during the bending out of the flanges, and lying between the flanges they form a support for the tread, such support never having been heretofore provided to my knowledge in a tread of this class. By the term "abrasive members" I mean the members held by the

flanges whether made of abrasive composition or metal appropriate for the purpose. 15

What I claim as my invention is:—

A safety or non-slipping tread comprising a sheet metal plate and strips of non-slipping material, said plate having pairs of flanges struck up to leave pairs of spaced openings between said flanges, the material between said openings affording bridge pieces serving to support said strips of non-slipping material held in place by said flanges. 20

WILLIAM R. ORMES.
